PERFORATING GUN FOR OIL WELLS

Frank C. Kniss, Eldorado, Ark.

Application May 22, 1937, Serial No. 144,276

8 Claims. (Cl. 164—0.5)

This invention relates to an improved perforating gun for use in wells, such as oil wells, and one object of the invention is to provide a gun which may be lowered into a well to a desired position therein and then discharged so that bullets with which the gun is loaded will be fired through the well casing and into walls of the well and thus serve to shatter the portions of the walls which have become clogged and cause 10 the oil to again flow freely.

Another object of the invention is to so form the gun that it may be freely lowered in the casing of the well and then manipulated by vertical movement which will cause gripping elements to be brought into engagement with the casing and mechanism then actuated to explode cartridges carried by the gun and discharge bullets through the well casing and into walls of the well.

Another object of the invention is to so construct the gun that it may be connected with the lower end of a string of tools ordinarily employed in an oil well when it is in use. It will thus be seen that no special apparatus is required for lowering the gun into the well and discharging the same and, therefore, a saving in equipment will be accomplished.

The invention is illustrated in the accompanying drawings, wherein

Figure 1 is a longitudinal sectional view through the improved gun showing the same as it will appear while being lowered into a well,

Figure 2 is a view similar to Figure 1 and illustrating the manner in which the gun is actuated 35 in order to discharge the gun,

Figure 3 is another view similar to Figures 1 and 2 and showing another position occupied by portions of the gun during firing thereof,

Figure 4 is an enlarged fragmentary sectional view taken vertically through the gun,

Figure 5 is a sectional view taken transversely through the gun along the line 5—5 of Figure 4,

Figure 6 is a sectional view upon an enlarged scale taken through the gun and the well casing along the line 6—6 of Figure 3,

Figure 7 is a view partially in side elevation and partially in vertical section and illustrating a gun of a modified construction,

Figure 8 is an enlarged sectional view of a portion of the gun illustrated in Figure 7,

Figure 9 is a view similar to Figure 8 illustrating a modified construction, and

Figure 10 is a fragmentary sectional view taken longitudinally through a gun of a modified construction wherein bullets are discharged from

opposite sides of the gun instead of from only one side thereof.

This improved gun is intended to be connected with the lower end of a string of well tools, one of which is indicated in general by the numeral 5 1, and it is to be understood that the string of well tools will be of a conventional construction and may include a jar which is also of a conventional construction and operated in the usual manner by reciprocating the string of tools vertically in the well. This string of tools and the gun will be forced downwardly through the well casing 2 which is of the usual tubular formation and consists of the usual series of pipe sections connected one with another.

The body portion 3 of the gun is in the form of an elongated metal bar having a neck 4 at its upper end carrying a head 5 from which projects a threaded shank 6 adapted to be secured into the lower end of the lowermost one of the 20 string of tools. The head 5 constitutes a wrench-engaging member by means of which the shank 6 may be screwed tightly into the well tool. This metal bar or body of the gun will be of such diameter that it will slide freely through the 25 well casing 2, and at one side the body is formed with a longitudinally extending groove or recess 7 which is of an even width throughout its length and has its upper portion of an even 30 depth and its lower portion 7a of gradually increasing depth and formed at its inner wall with side extensions or recesses 7b. A groove or recess 7c of less width than the inner wall of the groove or channel 7 is formed along the upper portion of the channel or there may be provided a series 35 of these grooves 7c in vertical spaced relation to each other.

Threaded sockets 8 which may be of any number desired are formed transversely of the body from one side thereof, and into these sockets are screw barrels 9 for receiving cartridges 10, it being understood that, in order to apply the cartridges, the barrels must be unscrewed, the cartridges thrust into the barrels from inner ends thereof, and the valves then again screwed 45 into the socket. The cartridges will thus be supported, as shown in Figures 1, 2 and 4, and each have its primer disposed in position for engagement by a firing pin 11. The firing pins are slidably received through openings 12 extending between the sockets and the inner wall of the upper portion of the groove or channel 7 and are engaged by the inner edge face of a firing bar 13 which is slidably received in the upper portion 50 of the channel 7 and held in engagement with 55

an abutment bar 14 by leaf springs 15. These springs 15 extend longitudinally of the channel and each has one end portion secured in one of the grooves or recesses 7^c and its free end portion bearing against the inner edge face of the firing bar. Confronting faces of the bar 14 and the firing bar 13 are formed with teeth 16 and 17, and from an inspection of Figure 4, it will be readily understood that, when pressure is applied to the lower end of the stem or shank 18 at the bottom of the firing bar to force this bar upwardly in the channel 7, a cam action will take place between the sloping edge faces of the teeth 16 and 17 to shift the firing bar toward the inner wall of the channel and thus apply pressure to the firing pin which will force the firing pin into the primers of the cartridges and thus explode the cartridges. When the cartridges explode, the bullets will be forced from the shells and through the well casing into the walls of the well and the walls of the well will be shattered to such an extent that flow of oil which has been stopped by clogging will be restored.

A block 19 is slidably received in the lower portion 7^a of the slot 7 and extends transversely therein, as shown in Figures 1, 2 and 3. The block tapers towards its upper end and along its inner side edge is formed with side extensions or ribs 20 which engage in the grooves 7^b and prevent this block from dropping through the open side of the slot when the device is not in use. The outer side edge of the block is beveled from opposite side faces of the block to form a cutting edge 21 which intersects the lower edge of the block to form a tooth 22 adapted to penetrate the well casing 2, as shown in Figure 3 and in Figure 6. From an inspection of Figures 1, 2 and 3, it will be seen that, when the block is in a lowered position, it will be entirely housed in the lower portion of the slot 7^a, whereas, when it is shifted upwardly, it will be caused to project from the open side of the slot and have biting engagement with the well casing, after which it will be forced through the well casing as the body 3 of the gun moves downwardly and it will eventually make contact with the lower end of the shank 18 to shift the firing bar 13 upwardly and cause the pins or plungers 11 to be forced into engagement with the primers of the cartridges and explode the cartridges. A barrier 23 closes the lower end of the slot and through this barrier is formed an opening 24 to slidably receive a rod 25. This rod constitutes means for moving the block 19 from the position shown in full lines in Figure 1 to that indicated by dotted lines, and in addition also serves as a hanger or carrier for a set of springs 26. These springs are formed from strips of resilient sheet metal and each has a vertically extending portion and upper and lower arms extending therefrom toward the rod 25. The ends of the arms are disposed in overlapping relation to each other and formed with aligned openings through which the rod passes. The arms are of such a length that, when the device is in use and thrust into a well casing, the vertically extending portions of the springs will have frictional binding engagement with the walls of the casing. By this arrangement the gun may be lowered into a well until it has reached a predetermined depth, at which time the string of tools will be drawn upwardly a sufficient distance to cause the rod to be drawn upwardly from the position shown in Figure 1 to that shown in Figure 2, and these springs will

well casing and also have tight binding engagement with the rod. The string of tools and the gun may be again lowered and, when the head at the upper end of the rod engages the lower edge face of the block 19, the block will be shifted upwardly to the position indicated by dotted lines in Figure 1. At this point the tooth 22 of the block will be brought into biting engagement with the casing 1 and the block will be held against further downward movement in the well casing. The string of tools and the gun may then be reciprocated vertically and the cam action which takes place between the block and the diagonally extending inner edge wall of the slot will cause the block to be gradually shifted radially of the gun and the well casing and the tooth 22 and the sharpened outer side edge of the block forced through the wall of the well casing. The weight of the string of well tools and the gun may be depended upon to force the block through the well casing to the position shown in Figure 3 or a jar of a conventional construction can be provided between the gun and the lower one of the string of well tools. It will be understood that the springs will be carried downwardly in the well with the gun during movement of the block to the position shown in Figure 3. Further reciprocating movement of the string of tools will cause the lower end of the shank 18 to engage the upper end of the block 19 and the firing bar 13 will then be forced upwardly and the cam action which takes place between the bar and the cam bar 14 will move the firing bar transversely and force the firing pins into engagement with the primers of the cartridges. The cartridges will then be exploded and the bullets discharged through the well casing and into the wall of the well to break up portions of the wall of the well and thus cause the well to flow freely.

Instead of discharging bullets from only one side of the gun, they may be discharged from opposite sides thereof, in which case a construction such as shown in Figure 10 will be employed. Referring to this figure, it will be seen that the upper portion of the slot 7 will extend through the body of the gun axially thereof and barrels 9 to receive the cartridges 10 will be mounted in diametrically opposed side portions of the body. The firing pins 27 which are slidably mounted in the pocket 28 extend into the slot 7 for engagement by the firing bar 29. These bars 29 are yieldably held against opposite side edges of a bar 30 by springs 31 which correspond to the springs 15 and contacting portions of the bar 30 and the firing bars 29 are formed with a tooth or serrated portion defining cooperating cam members 32 and 33. The lower end of the actuating bar 30 will extend into the widened lower portion 7^a of the slot 7 and terminate in a shank 34 corresponding to the shank 18 so that, when the device is in use and the lower end of the actuating bar is engaged by the block 19, the actuating bar will be shifted upwardly and the firing bars shifted transversely to force the firing pins into engagement with the primers of the cartridges and explode the cartridges. It will be obvious that additional sets of cartridges may be provided for the gun.

In Figures 7, 8 and 9, there has been shown another modified construction wherein the block 19 is eliminated and the firing bar 13 is slidably mounted in a slot 34 corresponding to the slot 7 but having its lower end communicating with a pocket 35 formed in the lower portion of the

body 3 instead of terminating in a deepened lower portion corresponding to the portion 7^a of the slot previously shown and described. The lower end of the pocket 35 is closed by a plug 36 having an axially extending bore 37 through which slidably passes a rod or plunger 38. Pins 39 are employed to secure the plugs in the lower end of the pocket or any other desired means may be employed. The upper end portion of the bore 37 is enlarged to form a socket 40 having threaded walls and the upper end of the rod 38 is formed with an enlarged threaded neck 41 carrying a disk-like head 42 and adapted to be screwed into the socket 40. It will thus be seen that the rod may be held stationary during lowering of the device into a well and that after it has been lowered to the desired position the string of tools and the gun turned in a direction to unscrew the neck from the socket. Instead of having the plug formed with a bore terminating in a threaded socket, it may be formed with a bore 43 of an even diameter throughout its length, as shown in Figure 9, in which case the rod 38 will be provided with a head-like disk 44 at its upper end corresponding to the head 42, but the threaded neck 41 will be omitted. When the construction shown in Figure 9 is used in place of that shown in Figure 8, a pin 45 is passed through aligned openings formed in the shaft or rod and the lower portion of the plug, and this pin will be formed of such material that, while it will prevent sliding movement of the rod through the plug during lowering of the gun into a well, reciprocating movement of the gun after the gun has been lowered to the desired position will cause the pin to be sheared and thus permit movement of the gun and the rod or plunger relative to each other.

At its lower end the rod or plunger 38 carries a block 46 which is of an inverted frusto-conical formation and constitutes a cam or wedge, and from the lower end of the wedge 46 extends a hollow guide 47 which is formed with longitudinally extending slots 48 in its opposed side portion. The head 49 at the lower end of the guide 47 is formed with a central opening 50 through which extends a rod 51 corresponding to the rod 25, and about this rod are disposed springs 52 corresponding to the springs 26. The upper end of the rod which is within the guide carries a head 53 of a diameter to be slidably received in the guide and from opposite sides of this head extend ears or lugs 54 which project outwardly through the slot 48 and are pivotally connected to lower ends of links 55. The links 55 extend longitudinally of the guide and at their upper ends are pivoted to ears 56 at the lower ends of dogs 57 which along their inner portions are formed with side ribs 58 engaged in undercut grooves 59 formed in opposite side portions of the wedge 46. From an inspection of Figure 7, it will be readily understood that after the gun has been lowered into a well and then drawn upwardly a short distance to expand the springs 52 and draw the rod 51 upwardly the gun may then be lowered and as it moves downwardly the guide 47 will slide downwardly along the upper portion of the rod with the head 53 moving upwardly in the guide and the wedge will cause the block or dog 57 to be moved radially in the well casing and the teeth formed upon the outer edge faces of the dogs will be brought into gripping engagement with the walls of the well casing. The gun may then be turned to unscrew the neck 41 from the socket 40 or a jaw carried by the string of

tools actuated to shear the pin 45 and the body of the gun may then slide downwardly along the rod 38 to bring the head 42 into engagement with the lower end of the shank 18 of the firing bar 13 and effect discharge of the cartridges. 5

Having thus described the invention, what is claimed as new is:

1. A well-shooting device comprising a body adapted to be lowered into a well casing, the body being formed with a longitudinally extending slot 10 and with transverse pockets, barrels in said pockets for receiving cartridges equipped with projectiles, firing pins for the cartridges carried by the body and extending into said slot, a firing bar mounted in said slot, said bar being slidable 15 longitudinally in said slot and shiftable transversely therein towards and away from said pins, means for shifting the bar towards the pins and moving the pins in a direction to discharge the cartridges when the bar is moved longitudinally 20 in one direction and cause the projectiles to perforate the casing, and means for sliding the bar in the said direction adapted to be actuated by reciprocating movement of the body in a well.

2. A well-shooting device comprising a body 25 adapted to be lowered into a well casing, the body being formed with a longitudinally extending slot and at one side of the slot being formed with transverse pockets and reduced passages leading from inner ends of the pockets to said slot, means 30 in said pockets for carrying cartridges equipped with projectiles, firing pins for the cartridges slidably received through the passages and projecting into the slot, a firing bar slidable longitudinally in said slot, a guide bar in said slot, the 35 firing bar and the guide bar being formed with cooperating cam portions for shifting the firing bar towards the pins and effecting discharge of cartridges when the firing bar is slid longitudinally in one direction whereby the projectiles will 40 penetrate said casing, springs in the slot for urging the firing bar toward inoperative position, and means carried by said body for effecting movement of the firing bar to operative position during reciprocation of the body in a well. 45

3. A well-shooting device comprising a body adapted to be lowered in a well casing, the body being formed with a longitudinally extending slot and a portion of the slot being formed with a diagonally extending inner wall, means for mounting in the body transversely thereof cartridges equipped with projectiles, firing pins for the cartridges slidably carried by the body and extending into the slot, a firing bar slidable longitudinally in said slot, a cam member for shifting the bar towards the pins and moving the pins in a direction to fire cartridges when the bar is slid upwardly in the slot and cause the projectiles to penetrate said casing, a block slidable longitudinally in the portion of the slot having the 50 diagonally extending inner wall and normally disposed at the lower end of the slot and entirely housed in the slot, means carried by the body for initially moving the block upwardly in the slot whereby the inclined wall will force the block 55 out of the slot and into biting engagement with a well casing and hold further downward movement of the block with the body, further downward movement of the body serving to bring the block into engagement with the lower end of the 60 firing bar and shift the bar upwardly to effect discharge of the cartridges. 65

4. A well-shooting gun comprising a body to be reciprocated within a well casing and having a longitudinally extending slot open along one 75

side of the body and having a lower portion formed with a diagonally extending inner wall, a barrier for the lower end of the slot, means for mounting in the body cartridges equipped with projectiles, firing pins extending into the upper portion of the slot through the inner wall thereof, a firing bar slideable longitudinally in the upper portion of the slot and shiftable transversely therein toward the firing pins whereby said firing pins will discharge the cartridges so that the projectiles will penetrate the casing, a guide bar mounted in the slot and having cam members for shifting the firing bar towards the pin when the firing bar is slid upwardly, a block 15 slideable longitudinally of the body in the lower portion of the slot, the block being housed in the slot when at the lower end thereof and being gradually movable outwardly through the open side of the block as it is moved toward the 20 upper end of the tapered lower portion of the block, said block being formed at its outer end with a tooth for biting into a well casing and having a sharpened edge for cutting through the well casing as the block is moved toward the upper end of the slot into position for engagement 25 with the lower end of the firing bar to effect upward movement of the firing bar, a rod extending through said barrier and depending from the lower end of said body, and springs loosely carried by the rod and extending laterally therefrom for engagement with walls of a well casing whereby the rod may be drawn upwardly through the springs as the body is drawn upwardly and maintained in the elevated position 30 to engage the block and shift the block upwardly into biting engagement with the well casing as the body is again moved downwardly.

5. A well-shooting device comprising a body formed with a longitudinally extending slot, 40 means for mounting in the body transversely thereof cartridges equipped with projectiles, firing pins for cartridges carried by the body and extending into the slot, a firing bar slideable longitudinally in the slot, said body having its lower portion formed with a pocket and said bar having 45 its lower portion extending into the pocket, a closure for the lower end of the pocket, a plunger slideable vertically through the closure and having a head at its upper end disposed within the pocket, means for releasably holding the plunger against movement relative to the body, the plunger when released being movable relative to the body whereby the body may be shifted downwardly along the plunger to move 50 the head of the plunger into engagement with the lower end of the firing bar and shift the bar upwardly into position to force the firing pin transversely of the body into position to dis-

charge cartridges and expel the projectiles therefrom, and means for engaging walls of a well casing and supporting the plunger in a stationary position in the well casing.

6. A well-shooting device comprising a body, 5 means for mounting in a body transversely thereof cartridges equipped with projectiles, a firing bar slideable longitudinally of the body and having its lower end extending into a pocket formed in the body, a plunger slideably carried 10 by the body with its upper end extending into the body and formed with a head for engaging the rod and shifting the rod upwardly when the plunger is held stationary, a wedge carried by said plunger and tapered downwardly, a cylindrical guide extending downwardly from said wedge and formed with side slots, a rod slideably carried by said guide with its upper end portion extending into the guide and provided with ears 15 extending outwardly through the slots, gripping 20 dogs slideably carried by said wedge, links connecting the dogs with said ears, and springs loosely carried by said rod and extending radially 25 therefrom for engaging walls of a well casing and holding the rod stationary. 25

7. In a well shooting gun, a body to be reciprocated in a well casing and having a slot, cartridge supporting means in the body, a cartridge carried in the cartridge supporting means, said cartridge having a projectile, a firing bar 30 movable in the slot, a firing pin for the cartridge, said firing bar being engageable with the firing pin for discharging the cartridge and perforating the well casing with the projectile, a block 35 movable in the slot and having a tooth for biting into a well casing, a rod slideable through the lower end of the body and being engageable with the block for urging said block into engagement with the firing bar for discharging the cartridge and causing the tooth to bite into the well cas- 40 ing upon reciprocation of the body.

8. In a device of the class described, a body adapted to be lowered into a well casing, said body being provided with means for holding a cartridge having a projectile therein, a firing 45 bar, a firing pin engageable by the firing bar for engaging the cartridge and discharging said cartridge so that the projectile will penetrate a well casing, said firing bar being movable, a block movable on the body and having a tooth 50 for biting into a well casing, a rod slideably connected with the body and engageable with the block for urging the block into engagement with the firing bar for discharging the cartridges and causing the tooth to bite into the well casing 55 upon reciprocation of the body.

FRANK C. KNISS.
